James Williams, of Philadelphia, Pa.
Assignor to
L. M. Williams & Co. of same place.
Letters Patent No. 1516, dated Jan. 7-1862.

The schedule referred to in these Letters Patent and making part of the same.

To all whom it may concern:

Be it known that I, James Williams of Philadelphia, County of Philadelphia, State of Pennsylvania, have invented or produced a new and original design for a Trade mark, and I do hereby declare the accompanying drawing with the following explanation of the same to form a full, clear and exact description of the said design.

My design for a trade mark consists of an oblong space bounded by the lines a, and a'; and the lines b, c, and b', c'; the upper portion of the said space having the words "Linen soap"; beneath which is the figure of a harp and beneath the latter the words "L. M. Williams & Co., Philada".

This mark I propose to imprint to bars of soap by moulding, stamping or otherwise, or the design may be printed on packages containing soap, or on other coverings for the same, or the design may be used in any other way in connection with the sale, manufacture or advertising of soap.

I claim the trade mark having the figure and letters represented in and by the accompanying drawing.

In testimony whereof, I have signed my name to this specification in the presence of two subscribing witnesses.
